UNITED STATES PATENT OFFICE.

CHALKLEY GRISCOM, LEWIS GRISCOM, AND JOHN P. GRISCOM, OF
MAHANOY PLANE, PENNSYLVANIA.

IMPROVEMENT IN PUMPS.

Specification forming part of Letters Patent No. 95,222, dated September 28, 1869.

To all whom it may concern:

Be it known that we, CHALKLEY GRISCOM, LEWIS GRISCOM, and JOHN P. GRISCOM, of Mahanoy Plane, in the county of Schuylkill and State of Pennsylvania, have invented a new and Improved Pump; and we do hereby declare that the following is a full, clear, and exact description thereof, which will enable others skilled in the art to make and use the same, reference being had to the accompanying drawings, forming part of this specification.

Figure 1 represents a vertical longitudinal section of our improved pump. Fig. 2 is a plan or top view of the same. Fig. 3 is a vertical transverse section of the same, taken on the plane of the line $x\ x$, Fig. 2. Fig. 4 is a detail vertical transverse section of the same, taken on the plane of the line $y\ y$, Fig. 2.

Similar letters of reference indicate corresponding parts.

This invention relates to a new pump to be used for mining and other purposes; and its object is to throw a continuous stream and to keep the water at an uninterrupted flow, so that when the column of water is once started it will continue to move so long as the pump is in motion. To more effectually obtain this object, besides a novel construction of pump, we connect the supply and discharge pipe with two double-acting reciprocating pumps, the cranks of which stand at right angles to each other, so that when the piston of one pump arrives at the end of the stroke the other piston will be at full work and will keep the column of water in motion.

We are aware that two single-acting pumps have already been used jointly for throwing a steady stream, but they can never be made to throw a continuous stream, and there will be the jar and loss of power caused by the frequent starting of the column. One double-acting pump will also labor under the same difficulty, and only where two double-acting pumps are used will a steady continuous stream be produced. The friction saved by the employment of two pistons for working four sets of valves will alone amount to a considerable saving.

Our invention consists also in a novel arrangement of the clack-chamber and in a new mode of connecting the piston-rod of the oper-

ating-cylinder with the pump rod or rods, all being so arranged as to produce the aforesaid steady stream with the least amount of power.

A B in the drawings are two steam-cylinders, arranged in a horizontal or other position parallel to each other or otherwise, as may be desired.

C D are two pump-cylinders, arranged, respectively, opposite to and in line with the cylinders A B. Upon each pump-cylinder is set a clack-chamber, E, and the clack-chambers of the two pumps are connected with each other by the branched suction-pipe F, and by the branched discharge-pipe G, as is clearly shown in Fig. 3.

H H are the piston-rods of the cylinders A B. I I are the piston-rods of the pump-plungers J J, that are to be moved back and forth in the cylinders C D. Each piston-rod H is connected with its opposite plunger-rod I by means of an upright yoke, K, into opposite sides of which both rods H and I are screwed or otherwise rigidly fastened. These yokes have lips a a, projecting from their outer sides, said lips fitting over or around the upper and lower edges of stationary guide-plates L, that are arranged on the bed of the machine, as indicated in Fig. 4. The inner faces of the yokes are grooved up and down, as in Figs. 1 and 2. Into these grooves fit the wrist-pins b of cranks c, formed on the opposite ends of a horizontal shaft, M, on which the fly-wheel N is mounted. As the piston-rods are drawn back and forth, they impart direct motion to the pump-plungers, and by means of the grooves in the yoke, and by the wrist-pins they also impart rotary motion to the fly-wheel shaft M. By means of this arrangement of the yokes K, the piston and pump rods may be as short or as long as may be desired, no extension connecting-rod being employed. For mining purposes this is very convenient, as the machine can be set up on a very contracted bed. Moreover, by the connection of the shaft, one engine, when the other is not to be used, can be employed to operate both pumps, or both engines may work one pump. In either case no other coupling will be employed. The cranks on the shaft M stand at right angles to each other. Thereby an effectual device for overcoming the dead-point is produced, as one engine is at the middle of

its stroke whenever the other is at the end, and thus one engine always serves to overcome the dead-point of the other engine. Another advantage of having the cranks arranged at right angles is to keep the column of water in constant motion, as when one pump-plunger is at the end of its stroke the other plunger will be at the middle of its stroke and the column of water will consequently be in constant motion, provided each pump is double-acting.

To prevent friction on the wrist-pins *b*, there are friction-rollers *d d*, arranged around them, as shown in Figs. 1 and 4. Each of the clack-chambers *E* is, by means of two diagonal partitions, *e e*, divided into four compartments, *f, g, h*, and *i*, as shown in Fig. 1. The two compartments *f* and *h* are respectively connected by means of channels *j j* with the ends of the pump-cylinder. The compartments *g* and *i*, which are between *f* and *h*, as shown, communicate, respectively, with the suction and discharge pipes. The partitions *e*, between the four compartments *f g h i*, are provided with four valves, *f', g', h',* and *i'*, as shown in Fig. 1, all of these valves opening upward.

The action of each pump will now be easily understood. If the plunger *J* moves in the direction of the arrow shown in Fig. 1, it draws the valve *g'* open by suction and draws the liquid from the suction-pipe into the chamber *g*, thence into *h*, and finally into the pump-cylinder. The same suction serves to keep the valve *h'* on its seat. At the same time the plunger will force the water in front of it into the chamber *f*, the water thus forced opening the valve *i'* and escaping into the discharge-pipe, the valve *f'* being closed. When the motion of the plunger is reversed, the water drawn in by the previous stroke will be forced out through the valve *h'*, while the suction will operate by opening the valve *f'*. A double-acting pump is thus produced, which keeps a constant stream in motion, except when the plunger arrives at either end of its cylinder. At that time, however, the plunger of the other pump is, owing to the position of the cranks on the shaft *M*, at the middle of its stroke, and keeps

the column of water in motion. In this manner a column of water is kept constantly moving, as when one pump stops the other will be working, and vice versa. All the shocks and jars consequent upon the interruption of the column of water are thus avoided, and so much friction is saved that the pumps can be worked much quicker than one single double-acting pump, or two connected single-acting pumps could ever be operated. By having the valves arranged diagonally, the corners in the clack-chamber are avoided and the water may move straight forward through the clack-chamber, as indicated by arrows in Fig. 1.

We claim as new and desire to secure by Letters Patent—

1. The yoke *K*, to which the steam-piston rod and the pump-plunger rod *I* are secured, when provided with the lips *a*, fitting around the upper and lower edges of the stationary guide *L*, and adapted to receive the crank-pins of the fly-wheel shaft *M*, all arranged as described, for the purpose specified.

2. The arrangement and combination with each other of the fly-wheel shaft *M*, crank-pins *b*, grooved sliding yokes *K*, stationary guides *L*, piston-rods *H H*, and plunger-rods *I I*, all arranged and operating substantially as herein shown and described, for the purpose specified.

3. A mining-pump consisting of two steam-cylinders, *A B*, of two pump-cylinders, *C D*, which have clack-chambers *E* with X-shaped partitions, both clack-chambers communicating with the suction and discharge pipes, as set forth, the piston and plunger rods being connected by means of sliding grooved yokes *K*, which drive the fly-wheel shaft *M*, the cranks *C'* of which stand at right angles to each other, substantially as described, for the purpose specified.
